UNITED STATES PATENT OFFICE.

ORIN KELLY, OF ATHENS, OHIO.

SCREEN.

1,145,316.

Specification of Letters Patent.

Patented July 6, 1915.

Application filed June 6, 1914. Serial No. 843,494.

To all whom it may concern:

Be it known that I, ORIN KELLY, a citizen of the United States, residing at Athens, in the county of Athens and State of Ohio, have invented a new and useful Screen, of which the following is a specification.

The device forming the subject matter of this application is adapted to be employed for screening materials of any sort, but to 10 avoid unnecessary repetition hereinafter, it will be presupposed that the structure is employed in handling coal.

One object of the present invention is to provide a novel arrangement of screens or 15 chutes, whereby the material may be graded according to its size, it being possible to make up combinations comprising the various sizes of graded material.

Another object of the invention is to provide a means whereby the material may be 20 made to travel along a screen or chute which is horizontally disposed, this operation being brought about by so proportioning a crank arm on a driving shaft and a rod connected therewith, that the rod, and consequently the screen will travel at different speeds at the ends of its stroke.

Another object of the invention is to provide a device of this type in which the 25 screens may be built in pairs and arranged to balance each other, thus reducing the shock, and rendering unnecessary, costly and massive foundations.

Another object of the invention is to provide a device of this type in which the 30 screens may be given different leverages upon a rock arm, thereby permitting one screen to be heavier than the other without causing undue shock in the operation of the 40 structure.

It is within the scope of the invention to improve generally and to enhance the utility of devices of that type to which the present invention appertains.

With the above and other objects in view which will appear as the description proceeds, the invention resides in the combination and arrangement of parts and in the 45 details of construction hereinafter described and claimed, it being understood that changes in the precise embodiment of the invention herein disclosed can be made within the scope of what is claimed without departing from the spirit of the invention.

In the accompanying drawing:—Figure 1 is a side elevation showing one form of the

invention; Fig. 2 is a longitudinal section of the structure shown in Fig. 1; Fig. 3 is a top plan of the structure shown in Fig. 1; Fig. 4 is a cross section on the line 4—4 of Fig. 2; Fig. 5 is a cross section on the line 5—5 of Fig. 2; Fig. 6 is a top plan showing a portion of one of the driving means whereby the screens are actuated; Fig. 7 is a vertical longitudinal section showing the 60 mechanism depicted in Fig. 6; Fig. 8 is a top plan showing a modified form of driving mechanism; Fig. 9 is a side elevation of the structure shown in Fig. 8; Fig. 10 is a side elevation showing a still further modification in the driving mechanism; Fig. 11 is a side elevation showing a modified form 65 of driving mechanism; Fig. 12 is a diagram referred to in connection with the operation of the structure; Fig. 13 is a fragmental top 70 plan of one screen; Fig. 14 is a section on the line 14—14 of Fig. 13.

In carrying out the present invention and referring particularly to Figs. 1, 2 and 4 there is provided an upper chute 1 and a lower chute 2 mounted to reciprocate in the direction of their lengths. These chutes may be supported for reciprocating movement in any desired manner, but in the present instance and by way of illustration 80 overhead supports 3 are shown, hangers 4 being employed for suspending the upper chute 1 from the supports 3, hangers 5 exercising a like function with respect to the lower chute 2.

The bottom of the upper chute 1 is divided into a plurality of sections, the number of sections being regulated by the number of grades into which it is desired to separate the material. In the present instance, the bottom of the upper chute 1 is depicted as comprising sections 6, 7 and 8. Openings 9 are formed in the section 6, the section 7 is provided with openings 10 and there are openings 11 in the section 8. The 85 openings 11 are the largest, the openings 9 are the smallest, and the openings 10 in size lie intermediate the openings 9 and 11.

In fashioning the openings 9, 10 and 11, inclined tongues 12 are struck from the bottom of the upper chute 1, as will be clearly understood from Figs. 13 and 14. Upon the back jerk of the upper chute 1, the coal or other material which is too large to pass through the respective openings, slides up 100 the inclined tongues 12. This construction 105 prevents the material from wedging in the

openings, reduces to a minimum the breakage on the screen or coal, and by permitting a free passage of the chute, reduces the power necessary to drive the chute.

- 5 Extended longitudinally of the lower chute 2 is a screen 14 of comparatively fine mesh, so that no coarser material can pass through the screen 14 than passes through the smallest openings 9 in the upper chute 1. 10 Below the screen 14, the chute 2 is provided with a longitudinally extended, trough-shaped pocket 15. At intervals, the pocket 15 is intersected by transverse spouts 16 and 17, there being openings in the screen 14 15 above the spouts 16 and 17, these openings being controlled by valves 18 and 19, actuated by any suitable means indicated at 20.

Extended across the lower chute 2 is an imperforate baffle plate 21. The baffle plate 21 at one end extends above the spout 16, and the other end of the baffle plate terminates adjacent the first of the openings 10. A baffle plate 22 is similarly mounted in the lower chute 2 and is located in a corresponding relation with respect to the spout 17 and the openings 11.

The numeral 23 indicates a supply bin of any desired sort beneath which reciprocates, upon a track 25, if desired, a feeder 24. 30 Any suitable means may be provided for reciprocating the feeder 24 but in the present instance the same is shown as operated through the medium of a pitman 26 pivoted to a crank arm 27 formed upon one end of a 35 shaft 28.

Presupposing that the device is to be employed for handling coal, the coal, mixed and of various sizes, is delivered onto the section 6 of the upper chute 1, through the 40 instrumentality of the feeder 24. The slack or coal of smallest diameter, passes through the openings 9 in the section 6 and drops into the slack pocket 15 and onto the baffle plate 21, from which the slack ultimately 45 finds its way into the pocket 15. As the lower chute 2 is reciprocated, the slack coal moves to the left and runs off the left hand end of the pocket 15.

The nut coal, which is the next largest 50 size passes through the openings 10 in the section 7 of the upper chute and drops onto the screen 14 or onto the baffle plate 22. Any slack produced by the passage of the coal over the sections 6 and 7 of the upper 55 chute passes through the screen 14 into the pocket 15 and mingles with the slack which originally passed through the openings 9 in the section 6 and through the left hand end of the screen 14. The nut coal travels to the 60 left along the screen 14 and ultimately is received by the spout 16. The egg coal passes through the openings 11 in the section 8 of the upper chute and moves to the left along the screen 14, the egg coal being 65 received by the spout 17. The lump coal

which is the largest size passes off the right hand end of the upper chute 1.

Obviously, any desired mixture may be effected by manipulating the valves 18. The function of the baffle plate 21 is to prevent 70 the slack coal passing through the section 6, from mingling with the nut coal which is moving to the left along the screen 14, the baffle plate 22 exercising a similar function with respect to the nut coal passing through 75 the section 7 of the upper chute and the egg coal moving to the left along the screen 14.

From the foregoing it will be obvious that the coal is first separated according to its size upon the chute 1 and then is re-screened 80 in the lower chute 2, it being possible to make up a combination of the various sizes of coals, at the will of the operator, by manipulating the valves 18 and 19.

It has been stated hereinbefore that the 85 coal moves to the left along the lower chute 2 but as will be set forth hereinafter the coal may be made to travel to the right along the lower chute 2. No matter how the coal travels upon the respective chutes 1 90 and 2, these chutes move in opposite directions and tend to balance each other.

I will now describe the various means whereby a reciprocating or shaking movement may be imparted to the chutes 1 and 2. 95

In the drawings, base frames 29 are shown, supporting for rotation a shaft 30. The shaft 30 may be connected operatively with the shaft 28 in any suitable manner. In the present instance, the shaft 30 is 10 shown as provided with a pulley 31 about which is trained a belt 32 passed around a pulley 33 on the shaft 28, although the showing of the drawings in this regard is 10 illustrative merely. The shaft 30 is provided with cranks 34 which project in a common direction, and with each crank 34 is assembled a short link 35, pivoted to a finger 36 projecting from a rock arm 37 mounted on a frame supported shaft 38. 11 The rock arm 37 is provided with a plurality of openings 39 in any of which may be placed pivot elements 40 united with connecting rods 41 and 42, the connecting rods 41 leading to the upper chute 1 and the connecting rods 42 leading to the lower chute 2. 11

In Figs. 8 and 9, a shaft 44 is journaled in suitable bearings 43 and is provided, in lieu of the crank 34, with the cranks 45 disposed at an angle of 180 degrees with respect to each other, the cranks 45 being connected through the medium of short links 46 with a rock arm comprising angularly disposed parts 47 mounted at their lower ends to swing upon a supporting shaft 48, the connecting rods which lead to the chutes or screens being denoted by the numeral 49.

As shown in Fig. 10, the drive shaft is depicted at 50, the crank thereon at 51, the short link being shown at 52. The rock arm 1

53 is pivoted intermediate its ends as shown at 54 and the connecting rods which lead to the chutes or screens are shown at 55.

In Fig. 11, the drive shaft is shown at 56 and carries an eccentric 57 surrounded by a strap 58 pivoted at 59 to a rock arm 60 supported for swinging movement intermediate its ends as shown at 61, the connecting rods being shown at 62.

10 As a general statement of operation, the device shown in Fig. 7 being taken as typical, it will be understood that when the shaft 30 is rotated, the crank 34, through the medium of the link 35 will swing the 15 rock arm 37 to and fro, the connecting rods 41 and 42 causing the chutes or screens 1 and 2 to move in opposite directions. This general statement of operation is applicable to the other forms depicted, but sun- 20 dry points of importance should be noted at this place.

In Fig. 12, the operation of the device is shown diagrammatically and this diagram will be applied to Fig. 10 by way of illustration, since it is in Fig. 10 that the simplest form of the invention is shown.

Suppose that the line AB represents the crank 51, that the line AC represents the link 52, that the length of the crank 51 is 30 six inches, and that the length of the link 52 is twelve inches. Then the length of the line BC is approximately ten inches. When the crank has moved through the first quadrant and has assumed the position BE, 35 the link will assume the position ED, the length of the line BD being eighteen inches and the outer end of the link having moved through a distance of eight inches, represented by the length of the line CD. As the 40 crank moves through the second quadrant and assumes the position BF, the outer end of the link will have moved through a distance of eight inches, represented by the line DC. As the crank moves through the third 45 quadrant and assumes the position BG, the outer end of the link will have moved through the distance CE, or approximately four inches. When the crank moves through the fourth quadrant to the position AB, the 50 outer end of the link will have moved through the distance EC or approximately four inches.

Now if the screen sets level or slants slightly up hill, it is evident that the coal is 55 propelled along the screen only by the momentum of the coal at the time that the direction of movement of the screen is reversed. Since the distance ED is greater than the distance EC it is obvious that the 60 lineal speed and consequently the momentum of the coal in the direction of the arrow X, at the time the crank assumes the position BE is greater than the momentum of the coal in the direction of the arrow Y at the 65 time the crank assumes the position BG.

Consequently, the coal will be advanced in the direction of the arrow X, even though the screens or chutes set level or assume a slight upward inclination.

If C represents the length of the crank 70 and L represents the length of the link, it will be seen that the operation above described takes place with maximum efficiency when, as in the present case, the relative lengths of the crank and the link approach 75 the following proportion: $C:L=1:1$.

The speed of advance of the coal along the chute or screen may be regulated by adjusting the relative lengths of the crank and the link but, in any event, the link should be 80 relatively short, compared with the crank.

The eccentric construction shown in Fig. 11 will operate satisfactorily under the conditions above outlined, although the simple crank and link constructions shown in Figs. 85 7 and 10 are preferable.

The constructions shown in Figs. 7, 10 and 11 will cause the coal to move in opposite directions on the two screens or chutes, whereas, when the construction shown in 90 Figs. 8 and 9 is resorted to, the coal will move in the same direction on both screens.

The principle involved consists in transforming the angular motion of a crank or eccentric into a lineal motion through the instrumentality of a rock arm, with the addition of a relatively short link when the crank is employed instead of the eccentric.

In practice, the screens or chutes 1 and 2 are seldom of the same weight, the lower 100 screen or chute being usually lighter than the upper one. In order to secure a perfect counter balancing of the screens or chutes, so as to reduce the shocks on a supporting structure to a minimum, it is necessary that 105 the momentum of the moving screens should be as nearly equal as possible. If the lower screen is lighter than the upper screen and, if the momentums of the screens are to be approximately the same, it is obvious that 110 the speed of reciprocation of the lower screen must be greater than the speed of reciprocation of the upper screen, since the momentum is the product of the weight and the speed. It is to accomplish this result 115 that the rock arm 37 is provided with a plurality of openings 39, it being possible to regulate and adjust the relative speeds of the two screens by mounting the pivot elements 40 respectively in the proper openings 39. Further, the lower screen generally should be run at a higher shaking speed than the upper screen, because the lower screen usually carries the finer grades of coal.

The invention includes, essentially, a rock 125 arm as 37 or 60, the reciprocating screens or chutes 1 and 2, connections, indicated at 41 and 42 or at 62, between the screens and the rock arm, a connection pivoted to the rock arm, the connection being in the form 130

of the strap 58 or the link 35, a shaft such as 56 or 30, and an eccentric element carried by the shaft, the eccentric element being of the form shown at 57 in Fig. 11, or consisting of the crank 34, the eccentric element, whatever be its form, being movably united with the connection, represented by such an element as 57 or 35.

Having thus described the invention, what is claimed is:—

- 10 1. In a device of the class described, vertically alined upper and lower chutes mounted for individual longitudinal reciprocation, the upper chute comprising sections having, respectively, openings of different sizes; a screen extended longitudinally of the lower chute and lying beneath both sections of the upper chute; an outlet spaced from the bottom of the lower chute 15 and intersecting the screen intermediate the ends of the screen; and a baffle in the lower chute and located above the screen, the baffle overhanging the outlet and terminating adjacent the outlet.
- 20 2. In a device of the class described, vertically alined upper and lower chutes mounted for individual longitudinal reciprocation, the upper chute comprising sections having, respectively, openings of dif-

ferent sizes; a screen extended longitudinally of the lower chute and lying beneath both sections of the upper chute; an outlet spaced from the bottom of the lower chute 35 and intersecting the screen intermediate the ends of the screen; a baffle in the lower chute and located above the screen, the baffle overhanging the outlet and terminating adjacent the outlet; and a valve operating in the lower chute and constituting a means for bridging the outlet.

3. In a device of the class described, a support; a rock arm mounted to swing thereon; means for actuating the rock arm; superposed screens; and means for connecting the screens with the rock arm at adjusted points along the rock arm, thereby to adjust the relative lineal speeds of the screens and to equalize the momentums of the screens when the same are of different weights.

In testimony that I claim the foregoing as my own, I have hereto affixed my signature in the presence of two witnesses.

ORIN KELLY.
